DESIGN FOR AN INDICATING PANEL OR SIMILAR ARTICLE

Michael Hallward, Boston, Mass., assignor to
Bendix Aviation Corporation, Baltimore, Md., a
corporation of Delaware

Application June 23, 1948, Serial No. 147,152

Term of patent 14 years

(Cl. D52—1)

To all whom it may concern:

Be it known that I, Michael Hallward, a subject of Great Britain and a resident of Boston, in the county of Suffolk and State of Massachusetts, have invented a new, original, and ornamental Design for an Indicating Panel or Similar Article, of which the following is a specification, reference being had to the accompanying drawing, forming part thereof.

In the drawing:

Figure 1 is a front view of an indicating panel or similar article, showing my new design, and

Figure 2 is a plan view of the indicating panel shown in Figure 1.

The characteristic features of my design reside in the portion shown in full lines.

I claim:

The ornamental design for an indicating panel or similar article, as shown and described.

MICHAEL HALLWARD.
